US00D739126S

(12) United States Design Patent
Fongher et al.

(10) Patent No.: US D739,126 S
(45) Date of Patent: * Sep. 22, 2015

(54) FOOTWEAR

(71) Applicant: CROCS, INC., Niwot, CO (US)

(72) Inventors: Federico Fongher, Villatora di Saonara (IT); Andrea Paolo Maritan, Noventa Padovana (IT)

(73) Assignee: Crocs, Inc., Niwot, CO (US)

() Term: 14 Years

(21) Appl. No.: 29/478,923

(22) Filed: Jan. 9, 2014

(51) LOC (10) Cl. 02-04

(52) U.S. Cl.

USPC D2/932; D2/929

(58) Field of Classification Search

USPC D2/25-942, 971

CPC A43B 21/00; A43B 21/02; A43B 21/06;

A43B 9/14

(57) CLAIM

The ornamental design for footwear, as shown and described.

DESCRIPTION

FIG. 1 is a front perspective view of footwear showing our new design;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The broken lines showing the CROCS® word mark, the tread pattern of the sole, the textual material on the sole, the textual material on the footbed, the raised bump pattern of the footbed, the holes at the end of each front strap, the holes at each side of the upper that are surrounded by the holes at the end of each front strap and the entire inside surface of the shoe upper, as well as the particular color in which embodiments of the design are depicted, are shown for illustrative purposes only and form no part of the claimed design.

1 Claim, 7 Drawing Sheets
